ABSTRACT OF THE DISCLOSURE

A stirrer includes a rotating shaft having an axial-flow type propeller secured thereto. A flow-guiding body is carried by the shaft downstream of the propeller and is interconnected with the shaft to transfer axial forces to the shaft opposing the force of reaction of the propeller to reduce the axial thrust to be carried by an associated shaft bearing.

A conventional type of stirrer for liquid fluids comprises a propeller secured to a rotary operating shaft. Such stirrers have a great transporting or pumping capacity as compared to stirrers of the type comprising a radial-flow turbine wheel secured to a rotary shaft. A disadvantage of the propeller-type stirrer, however, resides in the great thrust or compressive forces to which the propeller shaft is subjected in operation. The propeller shaft and its bearing means will have to be dimensioned for taking up such forces and, therefore, will necessarily be more expensive than the corresponding structural parts of a radial-flow turbine stirrer.

The present invention has for its object to provide for such improvements in a stirrer comprising an impeller in the form of a propeller as to minimize the thrust or compressive forces to which the impeller shaft is subjected in operation to thereby reduce the cost of manufacture of the impeller shaft and its bearing means.

For the object stated, according to the invention, a stirrer for liquid fluids comprising an axial-flow propeller secured to a rotary shaft is mainly characterized in that the impeller shaft carries at the downstream side of the propeller a flow-guiding body adapted to divert the initially axial liquid flow radially away from the shaft, thereby causing the propeller shaft to be subjected—in addition to a resultant axially directed force of reaction from the propeller—also to an oppositely directed force of reaction from said flow-guiding body, thereby reducing the axial thrust to be carried by the shaft-bearing means.

The invention will now be described more in detail with reference to the accompanying drawings, in which:

FIGURE 1, in a vertical cross-sectional view, illustrates a preferred embodiment thereof;

FIGURE 2, on a larger scale, shows the bottom-end portion of the stirrer shaft carrying the propeller and flow-guiding body; and

FIGURES 3 and 4 are views similar to that of FIGURE 2, but showing modified embodiments of the invention.

Referring now more specifically to FIGURE 1 of the drawing, a container 11 is shown which contains a liquid 12 and has disposed therein a stirrer generally designated by numeral 13. The stirrer 13 comprises a driving motor 14 having a stub-shaft 15 to which is rigidly connected, through a coupling 16, an operating shaft 17 having a propeller 18 secured to the bottom end portion

2

thereof. Beneath the propeller there is secured to this shaft, in accordance with the present invention, a flow-guiding body 19. This flow guide 19 is shaped as a body of revolution having a concavely curved generatrix and serves for diverting in a radially outward direction the vertically downward-directed liquid flow from the propeller. Mounted on the interior surface of the side wall of the container 11 are a plurality of suppressor vanes 20 projecting radially inward in vertical planes, respectively.

During rotation of the stirrer propeller 18, the latter, in cooperation with the flow guide 19 rotating together therewith, will cause the liquid to flow along paths as indicated by the arrows. The propeller will also impart to the liquid a rotational flow circumferentially within the container. The suppressor vanes 20, however, will be effective to reduce such circumferential flow whereby no harmful vortex formation will take place around the propeller shaft.

The forces created during rotation of the stirrer are illustrated in FIGURE 2. The blades of the propeller 18 are subjected to upwardly directed forces of reaction 22, which may be added to each other to form an upwardly directed resultant force 23 along the central axis of the shaft. The initially vertical fluid flow will be diverted by the flow guide 19 into radial directions, as indicated by arrows 21, and as a result of this the flow guide will be subjected to forces of reaction having downwardly directed components 24 the resultant sum of which, 25, will act downwardly along the central axis of the shaft. The resultant force to which the shaft is subjected will be upwardly directed and constituted by the force 23 less the force 25.

The components of the forces of reaction acting on the flow guide 19 which are directed at right angles to the shaft will tend to stabilize and to damp any lateral oscillations of the stirrer shaft 17 tending to occur in operation. A further improved damping action against oscillations will be attained if the flow-guiding body is made in the form of a downwardly open-ended hollow body which is filled with liquid, in which case the relatively large mass of such liquid will also have to be set in oscillatory motion when oscillations tend to occur.

The flow-guiding body 19 need not necessarily provide a continuously curved guiding surface for the liquid flow. As shown in FIGURE 3, the flow guide 19 is composed of a plurality of truncated cones 26, 27, 28 and a circular disc 29 projecting radially relative to the shaft. FIGURE 4 shows a flow guide 19 which is composed of one truncated cone 30 and a circular end disc 31. The flow guide need not rotate together with the shaft but could instead be carried rotatably by the same.

What I claim is:

1. A stirrer for liquids comprising a rotary operating shaft, an axial-flow type propeller secured to such shaft, a flow-guiding body carried by said shaft at the downstream side of the propeller and being adapted to divert the initially axial liquid flow radially away from the shaft, said flow-guiding body being interconnected with said shaft to transfer axially directed forces thereto thereby causing the shaft to be subjected to a force of reaction from said flow-guiding body which is oppositely directed to the axially directed force of reaction from the propeller to thereby reduce the axial thrust to be carried by an associated shaft-bearing means.
2. A stirrer for liquid fluids according to claim 1, char-

acterized in that said flow-guiding body is rigidly connected to the impeller shaft so as to partake in the rotation of said shaft.

3. A stirrer for liquid fluids according to claim 1, characterized in that said flow-guiding body is constituted by a body of revolution having a continuously concavely curved generatrix.

4. A stirrer for liquid fluids according to claim 1, characterized in that said flow-guiding body is composed of a number of truncated cones and a circular disc extending at right angles to the shaft. 10
